UNITED STATES PATENT OFFICE

2,090,276

ROTARY PUMP OR ENGINE

Charles Wheatley, Kansas City, Mo.

Application July 20, 1936, Serial No. 91,451

3 Claims. (Cl. 103—125)

My invention relates to a rotary pump or engine and one object is to provide a machine of this character which may, when power is applied thereto, be utilized for pumping water, air, or other fluid, or for transmitting power when supplied with a motive fluid, such for instance, as steam, compressed air, or the like.

Another object is to provide a machine of this character with one or more cylinders in each of which a rotor is operably mounted. Where a multiple of cylinders are employed the rotors are geared together so that they will operate at the same speed and if desired one cylinder may be supplied with motive fluid to drive the rotor therein so that it in turn will drive the companion rotors for pumping or other purposes.

A further object is to provide a machine of this character with a single rotary valve adapted to control the flow of fluid through all of the cylinders of the machine.

Other objects will hereinafter appear and in order that the invention may be fully understood, reference will now be had to the accompanying drawings, in which:

Fig. 1 is a front elevation of the machine.

Fig. 2 is a vertical sectional view on line 2—2 of Fig. 1 with some of the parts in elevation.

Fig. 3 is a broken vertical cross section on line 3—3 of Fig. 2 with some of the parts in elevation.

Fig. 4 is a fragmentary side elevation of the machine.

In carrying out the invention I provide a pedestal 2 provided in the present instance with an upper centrally disposed groove 4 and laterally disposed grooves 6 and 8 arranged below and at right angles to the groove 4. The grooves 4, 6 and 8 are equally spaced from a shaft 10 journaled in a bearing 9 and a bearing 12, which latter is located within the pedestal 2.

14, 16 and 18 designate cylinders having bases 20, 22 and 24 fitting snugly within the grooves 4, 6 and 8 and provided with flanges 23, 25 and 26, respectively, which are bolted or otherwise firmly secured to the pedestal 2. The cylinder 14 is arranged in a vertical plane while the cylinders 16 and 18 are arranged in a horizontal plane as best shown by Fig. 1. For convenience the pedestal 2 and the cylinders 14, 16 and 18 are made in halves which are removably connected by suitable means such as bolts 27 and 29, respectively. As the cylinders 14, 16 and 18 and their internal mechanisms are alike I will proceed to describe but one in detail.

As shown by Fig. 2 the cylinder 14 has an annular chamber 28 communicating at its lower

portion with an inlet 30 and an outlet 32 which, preferably, are arranged in axial alignment with each other as shown. The inlets 30 of the cylinders 14, 16 and 18 communicate with a manifold 31 and all of the outlets 32 communicate with a manifold 33.

Arranged concentrically within the cylinder 14 is a rotor 34 preferably of disk-like formation and provided with a peripheral head 38 adapted to traverse the chamber 28. Packing rings 40 embrace the head 38 to prevent leakage of fluid past the same when traversing the annular chamber 28. The rotor 34 is fixed upon an axially disposed shaft 42 extending transversely through the cylinder 14, which latter has stuffing boxes 44 located at each side thereof to prevent leakage of fluid around the shaft 42.

Suitable gearing such as bevel gears 46 and 46a are fixed to the respective ends of the shaft 42. The bevel gear 46 intermeshes with a similar gear 48 fixed upon a vertical shaft 50 extending axially through the cylinder 16 and provided with a fixed rotor 34a like the rotor 34. The bevel gear 46a intermeshes with a similar gear 52 fixed upon a vertical shaft 54 extending axially through the cylinder 18 and equipped with a fixedly mounted rotor 34b like the rotors 34 and 34a.

The shafts 42, 50 and 54 are journaled in bearings 60 fixed to the upper portion of the pedestal 2.

The shafts 50 and 54 are also journaled in bearings 62 and 64, respectively, secured to opposite sides of the pedestal 2.

66 designates a rotary valve which is common to the cylinders 14, 16 and 18 and fixed upon the shaft 10. The rotary valve 66 is of disk-like formation and provided with a peripheral gap or aperture 68 through which the respective rotor heads 38 pass in sequence during each revolution of said valve 66 and the rotor heads.

The rotary valve 66 is adapted to prevent fluid from passing directly from the inlets 30 to the outlets 32 of the respective cylinders, and for that purpose projects into transverse slots 72, 74 and 76 arranged in the cylinder bases 20, 22 and 24 midway between the respective inlets 30 and outlets 32, Figs. 2 and 3.

Timing gears 78 and 80, fixed upon shaft 10 and a shaft 82, respectively, serve to drive the rotary valve 66 at such speed as to successively carry the aperture 68 into position to allow the respective rotor heads 38 to pass in proper order. The shaft 82 is mounted in bearings 84 and provided at one end with a fixed pulley 86 and at its opposite end with a fixed bevel gear 88 which

meshes with a bevel gear 90 fixed upon the shaft 54. The pulley 86 may be used for transmitting power to the machine when the same is to be employed as a pump, or it may be used for transmitting power from the machine when the latter is operated as an engine.

By setting the rotor heads 38 in proper relation to each other and the aperture 68 and driving the rotors 34, 34a, 34b and the valve 66 at the same speed, there will be no danger of the rotor heads 38 colliding with the valve 66 when the machine is in operation, as the aperture 68 is of sufficient length to permit the passage of each rotor head in its proper turn.

From the foregoing description taken in connection with the drawings it is apparent that my machine may be utilized as a pump, or as an engine, or both as a pump and an engine when equipped with a multiple of cylinders and rotors. It is also apparent that the rotors 34 may be driven either in a clockwise or counterclockwise direction and when driven in the latter direction the inlet 30 becomes the outlet and the outlet 32 becomes the inlet. It is also apparent that the machine will operate successfully when equipped with but one cylinder and one rotor instead of a multiple thereof as shown.

While I have shown one form of my invention I reserve all rights to such other forms and modifications as properly fall within the spirit and scope of the invention as claimed.

Having thus described my invention, what I claim and desire to secure by Letters Patent, is:

1. In a machine of the character described, a pedestal provided with a central upper groove and laterally disposed grooves arranged below and at right angles to said upper groove, cylinders having bases secured within said grooves and each cylinder having an annular chamber provided with an inlet and an outlet, a rotor mounted in each cylinder and provided with a head adapted to traverse the annular chamber, a journaled shaft arranged centrally between the grooves in the pedestal, and a rotary valve fixed upon said shaft and arranged transversely to and

adapted to close the annular chambers, said valve having an aperture with respect to which the rotor heads are so positioned as to pass through said aperture in sequence at each revolution.

2. In a machine of the character described, a pedestal provided with a central upper groove and laterally disposed grooves arranged below and at right angles to said upper groove, cylinders having bases secured within said grooves and each cylinder having an annular chamber provided with an inlet and an outlet, a rotor mounted in each cylinder and provided with a head adapted to traverse the annular chamber, a journaled shaft arranged centrally between the grooves in the pedestal, a shaft on which each rotor is fixed, intermeshing gearing on the shafts to insure equal speed thereof, a rotary valve in the pedestal fixed upon said shaft and arranged transversely to and adapted to close the annular chambers, said valve having an aperture with respect to which the rotor heads are so positioned as to pass through said aperture in sequence at each revolution.

3. In a machine of the character described, a pedestal provided with a central upper groove and laterally disposed grooves arranged below and at right angles to said upper groove, a vertically disposed cylinder having a base secured in said upper groove, horizontally disposed cylinders having bases secured in the respective lateral grooves, each cylinder having an annular chamber communicating with an inlet and an outlet, a rotor mounted in each cylinder and provided with a head adapted to traverse the annular chamber, a journaled shaft arranged centrally between the grooves in the pedestal, a rotary valve fixed upon said shaft and arranged transversely to and adapted to close the annular chambers, said valve having an aperture with respect to which the rotor heads are so positioned as to pass through said aperture in sequence at each revolution, and gearing whereby the rotors and said valve are caused to rotate at the same speed.

CHARLES WHEATLEY.
